Inventor:

Fred T. Stevens

UNITED STATES PATENT OFFICE.

FRED T. STEVENS, OF BRYANT POND, MAINE.

INSTRUMENT FOR SQUARING STONE, &c.

SPECIFICATION forming part of Letters Patent No. 781,749, dated February 7, 1905.

Application filed October 9, 1903. Serial No. 176,341.

To all whom it may concern:

Be it known that I, FRED T. STEVENS, a citizen of the United States of America, and a resident of Bryant Pond, Oxford county, State 5 of Maine, have invented certain new and useful Improvements in Instruments for Squaring Stone, &c., of which the following is a specification.

My invention relates to an instrument by 10 which may be described or marked off correctly for dressing purposes stone, wood, iron, or any like material where a perfect plane right-angle batter or incline is required.

In dressing rectangular stone it is customary 15 to first cut two adjacent edges and then cut the other two edges in the same plane. To get the last two edges in the same plane as the first two is not an easy thing to do, and it is commonly done by sighting across 20 straight-edges—an inaccurate method.

My invention is designed to locate parallel edges in the same plane with each other by measuring their inclination to the horizon.

It consists, essentially, of an elongated base, 25 to which is pivoted an arm normally parallel with the base, this arm being provided with one or more spirit-levels and means for clamping the arm in various positions.

I illustrate my invention by means of the 30 accompanying drawings, in which—

Figure 1 is a side elevation, and Fig. 2 is a plan of my tool or instrument.

A is an elongated base provided with perforated lugs adapted to attach it to a straight- 35 edge, and C is an arm pivoted to the base and normally resting on it and parallel with it. The arm C is provided with a horizontal spirit-level *d* and a vertical level *e*, both being at or near the end of the arm.

Means are provided for clamping the arm 40 C at any desired angle with the base and for this purpose, as here shown, I form a segment B, integral with the base and extending upward. The segment may be graduated, as 45 shown, along its edge, and it has a segmental slot *b*, through which passes the clamping-screw *c*, by which the arm is clamped at any angle with the base.

The instrument is used as follows: In cutting stone after the two adjacent edges are 50 cut the base is laid on one of the edges either directly or attached to a straight-edge, and if it is not perfectly level the arm is raised until it is level. The instrument is then shifted to the opposite and parallel edge, and if the arm 55 is still level the two edges are in the same plane—that is, they are at the same angle with the horizon. Thus parallel edges may be tested on timber, iron, or any like material. If the edge to be cut is at right angles 60 in a vertical plane, the implement is turned up so that the level *e* is central. Thus in cutting a rectangular stone all of the faces can be squared by the use of my device applied from one edge to the corresponding parallel 65 edge and the right-angle edges. It is simple in construction and may be cheaply made, and when the segment is properly marked or graduated any desired batter or incline may be described, thus making the uses of the instrument numerous.

It will be understood that the graduation of the segment may be such that either the angle may be read or the number of inches of inclination or batter per foot which the 75 angle will give. When thus graduated, the instrument will work equally well with a batter as with plane work.

I claim—

The herein-described instrument, consisting of an elongated base A, a segment secured thereto and extending vertically upward therefrom, said segment being provided with a curved slot through the body thereof parallel with the curvature of the segment, an 85 arm pivotally secured near the apex of the segment provided with a head having recesses or depressions at right angles to each other, one upon the outer face of the end and one upon the top face of the end, a horizontal 90 spirit-level mounted in the depression upon the top face of the end, and a vertical spirit-level mounted in the other depression, and a clamping means passing through and slideable in said slot and engaging said arm intermediate of its length for holding the arm in the 95

proper position relative to the segment, said
clamping means comprising a plate adapted
to contact the segment opposite the slot, a
threaded member passing through the slot
5 and arm, and a thumb-nut mounted upon said
member adapted to engage the arm and clamp
it and the segment together.

Signed at Bryant Pond, Maine, this 11th
day of September, 1903.

FRED T. STEVENS.
